UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, ENGLAND.

AMMUNITION HOISTING AND LOADING APPARATUS OF HEAVY ORDNANCE.

1,188,630.

Specification of Letters Patent. Patented June 27, 1916.

Original application filed December 31, 1912, Serial No. 739,438. Divided and this application filed March 24, 1914. Serial No. 826,860.

To all whom it may concern:

Be it known that we, ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in Ammunition Hoisting and Loading Apparatus of Heavy Ordnance, of which the following is a specification.

This invention relates to ammunition hoisting and loading apparatus of the kind in which the powder charges and the projectile are raised in lower cages from the magazines to a working chamber, wherein the said powder charges and projectiles are transferred from the lower cages to intermediate or waiting receivers and thence to the upper or gun loading cage by which they are carried to the breech of the gun.

The chief object of the present invention is to provide improvements in the mechanism constituting hoisting and loading apparatus of the above stated kind.

According to this invention, in order to obviate the necessity of providing a long bridge for the projectile during its transference from the cage to the receiver, the powder and projectile cages are carried on separate rails (but not in separate compartments) in the trunk and the powder cage rails are deflected inward relatively to the projectile cage rails in order to bring the projectile cage into close proximity to the tray of the waiting receiver.

In order that the said invention may be clearly understood and readily carried into effect we will describe the same more fully with reference to the accompanying drawings in which:—

Figure 1 is a view showing a constructional form of the hoisting and loading apparatus, and Fig. 2 is a section taken approximately on the line 4, 4 of Fig. 1.

A is the working chamber that moves with the turret during training, B is the gun loading cage that conveys the ammunition from the working chamber to the gun,

B' is the movable powder holder and B² the projectile tray of the said cage.

C is the rotary trunk and D is the powder room from which the powder charges are loaded by means of the trays d into the powder cage D'.

E' is the projectile cage that is loaded by means of the bogie e from the projectile room E.

D^x and E^x represent the powder charge receiver and the projectile receiver in the working chamber.

In the constructional form of the invention shown the rails c', c² for the cages D', E' respectively are arranged parallel to one another for a certain distance above the floor of the projectile room. Above this point the rails c² remain parallel to each other while the rails c' are inclined toward each other and meet at a point above the highest position that the cages D' assume. In this manner after the cages D', E' ascend above the level of the powder room D, the cage E' moves parallel to the axis of the truck and the cage D moves toward the said axis. By these means it is possible to reduce the distance through which the projectile moves during its transference from the cage E' to the receiver E^x. The relative lateral movement that takes place between the cages D', E', during their ascent is utilized for locking them together. For this purpose a bolt e^{2x}, is, in the example shown, attached to the top of the cage E', and this bolt is adapted to engage in a vertical groove in the underside of the cage D' as soon as the cage E' reaches the cage D'. The said vertical groove terminates in a horizontal groove d^{2xx} with which the bolt e^{2x} engages during the aforesaid lateral movement that takes place between the cages. The cages are in this manner compelled to descend together until the cage D' reaches the magazine floor, whereupon the bolt e^{2x} comes opposite the aforesaid vertical groove and the cage E' is released to permit it to be lowered to the projectile room E.

What we claim and desire to secure by Letters Patent of the United States is:—

1. In ammunition hoisting apparatus, the

combination with the lower powder charge and projectile cages, and the rotary trunk, of vertical rails for the projectile cage and rails for the powder charge cage, the upper ends of the latter rails being deflected inwardly, so that when the powder charge cage is in its uppermost position, it is situated nearer the axis of the trunk than is the projectile cage.

2. In ammunition hoisting apparatus, the combination with the lower powder charge and projectile cages, and the rotary trunk, of vertical rails for the projectile cage, inwardly deflected rails for the powder charge cage, and means for causing the lateral movement between the two cages to effect the locking of one cage to the other.

3. In ammunition hoisting apparatus, the combination with the lower powder charge and projectile cages, and the rotary trunk, of vertical rails for the projectile cage, inwardly deflected rails for the powder charge

cage, and a pin on the projectile cage adapted to engage in a horizontal slot in the under side of the powder charge cage.

4. In ammunition hoisting apparatus, the combination of a powder charge receiver, a projectile receiver located to the outer side of the powder charge receiver, lower projectile and powder charge cages, vertical rails for the projectile cage to bring the same to the inner side of the projectile receiver, and rails for the powder charge cage having their upper ends deflected inwardly to bring the powder charge cage to the inner side of the powder charge receiver.

In testimony whereof we affix our signatures in presence of two witnesses.

ARTHUR TREVOR DAWSON.
JAMES HORNE.
